UNITED STATES PATENT OFFICE.

JOHN H. ASTRUCK, OF NEW YORK, N. Y.

DESIGN FOR A COIN-TRAY.

43,261.

Specification for Design.

Patented Nov. 26, 1912.

Application filed June 8, 1912. Serial No. 702,574. Term of patent 7 years.

To all whom it may concern:

Be it known that I, JOHN H. ASTRUCK, a citizen of the United States, residing in New York city, county and State of New York, have invented a new, original, and ornamental Design for Coin-Trays, of which the following is a specification, reference being had to the accompanying drawing, forming part thereof.

Figure 1 is a plan of a coin tray showing

the design; Fig. 2 an end view looking in the direction of the arrow Fig. 1, and Fig. 3 a side view.

I claim:

The ornamental design for a coin tray, as shown.

JOHN H. ASTRUCK.

Witnesses:

FRANK V. BRIESEN,
KATHERYNE KOCH.
